ATTORNEY

UNITED STATES PATENT OFFICE

155,547

DESIGN FOR A PHONOGRAPH RECORD
HOLDER

Milton B. Smith, Huntington, Ind., assignor to
The Hettrick Manufacturing Company, Toledo,
Ohio, a corporation of Ohio

Application April 15, 1948, Serial No. 145,741

Term of patent 7 years

(Cl. D33—2)

To all whom it may concern:

Be it known that I, Milton B. Smith, a citizen of the United States and a resident of Huntington, Huntington County, Indiana, have invented a new, original, and ornamental Design for a Phonograph Record Holder, of which the following is a specification, reference being had to the accompanying drawing, forming a part thereof.

In the drawing:

Figure 1 is a top perspective view of the phonograph record holder, showing my new design; and

Figure 2 is a top plan view of the phonograph record holder.

I claim:

The ornamental design for a phonograph record holder, as shown.

MILTON B. SMITH.
